UNITED STATES PATENT OFFICE.

ALEXANDER BOGDÁNFFY, OF NEW YORK, N. Y., ASSIGNOR TO THE INTERNATIONAL CORK COMPANY, OF BROOKLYN, NEW YORK, A CORPORATION OF NEW YORK.

MACHINE FOR THE MANUFACTURE OF BOTTLE-CLOSURES.

1,249,714.

Specification of Letters Patent. Patented Dec. 11, 1917.

Application filed December 9, 1914, Serial No. 876,252. Renewed May 14, 1917. Serial No. 168,596.

To all whom it may concern:

Be it known that I, ALEXANDER BOGDÁNFFY, a subject of the King of Hungary, and a resident of the city of New York, in the county of Kings and State of New York, have invented certain new and useful Improvements in Machines for the Manufacture of Bottle-Closures, of which the following is a specification.

10 The present invention relates to a machine for the manufacture of closures or stoppers for bottles or like receptacles, more particularly it relates to a machine for making closures of the cap variety, including those 15 termed "crown corks". Closures of this type consist of a metallic cap or crown to be locked to the exterior of the neck of the bottle, and of a sealing disk or packing of cork or the like, which is united by the aid 20 of a suitable cementing medium with the cap or crown. There may be either used a fusible cementing medium which is fused when in the cap or crown and left to cool and set, or the cap or crown is charged with a liquid 25 or viscous cementing material, which is caused to set or to coagulate, as the case may be.

The main objects of the present invention are to provide a simple and effective machine for carrying out a method or process 30 for the manufacture of closures of the second type, that is to say in which a union between the metallic cap and the sealing disk or packing is obtained by the aid of a liquid or viscous cementing medium which 35 is set or coagulated, for instance, by subjecting the assembled closure to heat.

With these and other objects in view, which will more fully appear as the nature 40 of the invention is better understood, the same consists in the combination, arrangement and construction of parts hereinafter fully described, pointed out in the appended claims and illustrated in the accompanying 45 drawings, it being understood that many changes may be made in the size and proportion of the several parts and details of construction within the scope of the appended claims without departing from the spirit 50 or sacrificing any of the advantages of the invention.

One of the many possible embodiments of the invention is illustrated in the accompanying drawings, in which:—

55 Figure 1 is a front elevation of a machine

constructed in accordance with the present invention; Fig. 2 is a rear elevation of the same; Fig. 3 is a vertical central section taken through the same; Fig. 4 is a section taken on line 4—4 of Fig. 3; Fig. 5 is a section taken on line 5—5 of Fig. 3; Fig. 6 is a section taken on line 6—6 of Fig. 3; Fig. 7 is a section taken on line 7—7 of Fig. 3; Fig. 8 is a section taken on an enlarged scale through the top portion of the machine; Fig. 9 is a section taken on line 9—9 of Fig. 8; Fig. 10 is a section, taken on a larger scale through the upper portion of the detail shown in Fig. 8; Fig. 11 is a section taken on line 11—11 of Fig. 10; Fig. 12 is a side elevation of one of the cams shown in Fig. 8; and Fig. 13 is a plan view of the detail shown in Fig. 12.

In the drawings, the numeral 20 indicates the main frame of the machine, including a horizontal table 21. On this table is mounted a vertically disposed, cylindrically bored column 22, that is closed at its upper end by a head 23, its lower open end having a flange 24, the latter resting upon the table, and being attached thereto in any suitable manner. Within the column and in the longitudinal axis thereof is disposed a shaft 25. This shaft is mounted rotatably in the head 23 of said column and in a step bearing 26, that is formed upon the table 21. Set screws 27 and 28, bearing against the ends of the shaft, serve to adjust the position of the latter in relation to the table. To the shaft 25 is fixedly attached a disk 29, and to the latter is fastened a transporting wheel 30, that is disposed above the table and is, preferably, made in the form of a star wheel, having recesses 31, to which the metallic caps of the closures are fed in any suitable manner in their inverted positions. The flange 24 of the column is provided with an annular groove 24' in its underface in alignment with the recesses of the star wheel, thereby forming a guide for keeping the caps in position upon the transporting wheel. The transporting wheel is intermittently rotated in the direction of the arrow shown in Fig. 7 of the drawings by the main driving shaft 32 of the machine. This shaft is journaled in bearings 33, which are formed upon the main frame, and carries a loose pulley 34 and a fixed pulley 35, the latter being adapted to be geared to any suitable driving means. To the driving shaft 32 are 110

keyed two eccentrics 36, with the straps of which are connected in the usual manner rods 37, the latter being pivoted to a head 38, substantially in the form of a ring, which 5 is reciprocably mounted upon the column 22. To the head 38 are fastened, for instance by means of screws 39, two blocks 40, which are seated in longitudinal slots 41 in the said column. Each block 40 is made of 10 two sections, denoted by the numerals 42 and 43 (Fig. 9), in engagement with the pointed ends 44 of adjusting screws 45, which are screwed into the head 38 and serve to dis- tend the two sections of the blocks, so that 15 they, on adjusting the screws 45, extend throughout the widths of the slots. The blocks are disposed on diametrically opposite points of the head 38, and have each attached thereto a cam 46, said cams being located 20 within the column 22 and are adapted to coöperate in a manner presently to be de- scribed with lugs 47, upon which are mounted anti-friction rollers 48, said lugs being carried by a sleeve 49, that is loosely held 25 upon the shaft 25 and provided upon its upper end with a flange 50, on which are formed ratchet teeth 51, that are adapted to coöperate with pawls 52. These pawls are carried by pins 53, which are horizon- 30 tally disposed in a disk 54, that is fastened by screws 55, or otherwise, to a flange 56, the latter being fixedly attached to the shaft 25. The pawls are held by springs 57 continu- 35 ously in engagement with the ratchet teeth of the flange 50. A spiral spring 58 is wound around the sleeve 49, its outer end being attached to the column 22 and its inner end to the sleeve 49 for a purpose hereinafter to be described. With the disk 40 54 is associated a brake mechanism, com- 45 prising, for instance, two brake blocks 59, which project through apertures 60 in the column and are provided with brake linings 61, which contact with the disk 54. The blocks are pivoted at 62 to levers 63, the lat- 50 ter being fulcrumed at 64 to the column. The free ends of the levers 63 are connected by a spring 65, which keeps the brake blocks continuously in engagement with the 55 disk 54. Each of the cams 46 is provided with a straight upper portion 66, a screw thread-like middle portion 67 and a straight lower portion 68. The straight portions of the cams are disposed vertically, as clearly shown in Fig. 12 of the drawings.

The operation of the device so far de- 60 scribed is as follows: When the head 38 and the parts carried thereby are in their upper positions (Fig. 3), the anti-friction 65 rollers 48 upon the lugs 47 are in engage- ment with the lower straight sections 68 of the cams, the spring 58 causing the anti- friction rollers to abut against the said cams. As now, in the rotation of the main driving shaft 32, the head 38 and the parts

carried thereby commence their downward stroke, the sleeve 49 and thus the shaft 25 will be kept stationary until the anti-friction rollers 48 coöperate with the screw thread-like portions 67 of the cams. During such time, the sleeve 49 is turned in the direction of the arrow shown in Fig. 7 of the drawings, a motion in the same direc- 70 tion being imparted by the intermediary of the ratchet teeth and the pawls to the shaft 25 and thus to the transporting wheel 30. As the downward stroke of the head 38 is continued and the anti-friction rollers 48 contact with the upper straight portions 66 of the cams, the transporting wheel is kept 75 stationary. During the upward stroke, the shaft 25 remains stationary, the sleeve 49, however, is returned to its initial position by the spring 58, which causes the anti- friction rollers 48 to follow the cams 46. The brake mechanism above described 80 serves to prevent the disk 54 from turning too far, that is to say it causes the shaft 25 to stop as soon as the anti-friction rollers engage with the straight portions of the 85 cams.

The caps may be passed to the recesses of the transporting wheel either manually or automatically. An automatic device is disclosed in the drawings. This device co-acts with a charging chute 69, into which the caps are brought in their inverted positions automatically in any suitable manner. The chute leads to a channel 69' on the table. On the table is formed a guide 70 at right angles to the channel 69', and in this guide is held by means of a cover 71 a slide 72. The cover 71 closes also the channel 69'. The cover is removable, and is held in place by means of a clamp 73, which is pivoted at 74 to the table. Upon disengaging the clamp from the cover 71, the latter may be removed from the machine. The slide 72 is actuated by a bellcrank lever 75, which is fulcrumed at 76 to the main frame and engages with the said slide. The other end of the bellcrank lever is connected by a link 77 with the strap of an eccentric 78, the latter being keyed to the main driving shaft 32. The relation between the eccentrics 78 and 36 is such that, when the transporting wheel is at rest, the slide 72 is caused to move toward the same, thus seat- 100 ing a cap in the recess registering with the guide 70.

The caps received from the chute 69 are transported step by step by the transport- 105 ing wheel in the direction of the arrow shown in Fig. 7 of the drawings, and are brought, one after the other, into register- 110 ing position with the means which intro- duces into the same the cementing medium. This means comprises a receptacle 79, com- 115 municating through a pipe 80 with a valve casing 81. The receptacle 79, the pipe 80 120

130

and the valve casing 81 are attached to the head 38. Within the valve casing is disposed a valve 82, which carries at its upper end a disk 83, that is provided with a plurality of apertures 84, through which the liquid cementing medium is adapted to flow toward the valve. A spring 85, bearing against the disk 83, keeps the valve upon its seat, and projects a pin 86, that is made integral with or attached to the said valve, through the discharge opening 81' in the valve casing. Upon the downward movement of the head 38, and when the anti-friction rollers 48 coact with the upper straight portion 66 of the cams, that is to say when the transporting wheel is at rest and a cap is held in registering position with the cementing medium charging means, the pin 86 is caused to bear against the inner face of the cap, whereby the valve is lifted from its seat and the desired amount of liquid cementing medium is introduced into the cap. Upon the upward stroke of the head 38, the valve is obviously seated by the spring coacting therewith.

The cementing material having been introduced into the cap, the latter is transported to means which spreads the said cementing material over the entire inner face 30 of the head of the cap. This means comprises in the case illustrated in the drawings a vertically disposed spindle 87, which is rotatably and reciprocably mounted on the head 38. Suitable means is provided which 35 causes the spindle to reciprocate with the head 38, for instance a nut 88, which meshes with the upper screw threaded end of the spindle, a ball bearing 89 preventing friction between the head and the spindle. 40 Upon the spindle is mounted a pulley 90, against which bears the lower end of a spring 91, that is coiled around said spindle, the upper end of said spring bearing against a ball bearing 92, which abuts against the head 38. Rotation is imparted to the spindle by a belt 92', which runs over a pulley 93, that is mounted upon the main driving shaft 32, and over the pulley 90, which is, as above described, attached to the spindle 45 87, suitable idlers 94 guiding the said belt. To the lower end of the spindle is attached a block 95, for instance of rubber. The reciprocating head 38 carries with it the spindle 87, which rotates continuously. When 50 the head 38 is near the end of its down stroke, the block 95 is brought into contact with the inner face of the cap. When in such contact, the rotary block spreads the liquid cementing material over the entire 55 inner face of the head of the cap, which may be held against rotation by any suitable means, (not shown). The head upon its further downward movement compresses the spring 91. When the head moves upward, 60 it leaves the block 95 in contact with the

inner surface of the cap until the upper face of the head 38 contacts with the ball bearing 89 and thereby carries the spindle with it. The purpose of carrying the spindle slidably upon the head 38 is to permit 70 the said spindle to remain for some time within the cap so that it is able to perform the spreading operation properly. If no sliding motion were permitted between the head and the spindle, the latter would stay 75 for a moment only in the cap, inasmuch as the head starts its upward stroke immediately after it has finished its downward stroke. It is to be observed that the block 95 need not be rotated; it will spread the 80 cementing medium by being pressed against the inner face of the cap.

After the cementing material has been spread over the surfaces of the caps, the same are transported, one after the other, to 85 an assembling plunger 96, that is attached to the head 38. The sealing disks are placed into a vertical tube 97, which is secured to the table 21 by means of a bracket 97'. The sealing disks are fed by gravity, or otherwise, into a guideway 98 of a plate member 99, which is attached to the flange 24 of the column 22 above the transporting wheel. The plate member is provided with an aperture 100 in alignment with the plunger 96 95 and in registering position with an aperture 101 in the flange 24 of the column 22. The sealing disks are conveyed in the guideway 98 from below the tubular member 97 to the apertures 100 and 101 by a reciprocable conveyor 103, which is slidably arranged in the guideway 98 and pivoted to a lever 104, that is fulcrumed at 105 to the frame of the machine. The lever 114 is connected by means of a universal joint 104' with the strap of an 100 eccentric 106, the latter being keyed to the main driving shaft of the machine. The conveyor 103 engages the sealing disks and transfers the same to the apertures 100 and 101. Obviously the angular relation between 105 the eccentrics 106 and 36 must be such that, when the head 38 is on its upward stroke, the conveyor 103 will move toward the transporting wheel and thereby transfer a sealing disk within the reach of the plunger 96, 110 which, in its downward movement, forces the sealing disk through the apertures 100 and 101 into the metallic cap on top of the cementing material therein.

As it happens sometimes that one or the 120 other of the recesses in the transporting wheel does not contain a metallic cap, it becomes necessary to eject the sealing disk from that recess after it has passed the plunger 96. For this purpose there is slidably disposed upon the head 38 a spindle 107, that is provided upon its upper end with a stop 108 and near its lower end with a disk 109. Against this disk and the head 38 bears a spring 110, that tends to force the 125

spindle downward toward the transporting wheel. The spindle 107 is disposed upon the head 38 in such a manner that it is in registering position with a recess in the transporting wheel when the latter is at rest. When, therefore, the head 38 moves downward, the spindle 107 will enter such recess in the star wheel. If an assembled crown cork is seated in this recess, the spring 110 will be compressed by the upward movement of the spindle 107. If, however, a sealing disk only is seated in the said recess, the spindle 107 will force the same through an opening in the table of the frame so that it will fall into a receptacle below said opening, for the reason that the tension of the spring 110 is greater than the resistance offered by a sealing disk in a recess of the transporting wheel.

20 The assembled crowns slide down an inclined passage 111 to a heating and uniting head 112. This head comprises an annular member 113, having spider-like arms 114, the latter being made integral with a hub 115. This hub is keyed or otherwise attached to a shaft 116, which is journaled in bearings 117 and 118, the latter being, preferably, made integral with the main frame of the machine. This shaft is continuously driven from the main driving shaft, and for this purpose the latter is provided, for instance, with a worm 119, meshing with a worm gear 120, that is fixedly attached to the shaft 116. Upon the annular member 113 are formed a suitable number of radially extending and outwardly projecting ribs 121, which are covered by an annular curved flange 122, whereby a plurality of curved passages 123 are formed in the uniting head, said passages registering, as the said head is being rotated, with the inclined passage 111, and receiving thus, one after the other, assembled crowns from the said passage 111. The flange 122 is formed upon a cylinder 122', that is attached by screws or otherwise to the ribs 121. The crowns are arrested in their downward motion in the passages 123 by a stationary arch-shaped platform 124, which projects between the annular member 113 and the flange 122, and is attached to the arm 125 of a ring 126, which is drawn over the hub 115. The ring 126 is kept stationary by arms 127, which engage with downwardly projecting lugs 128 of a bridge 129, that is fastened to the table 21. Plungers 130 are slidably arranged in the cylinder 122' in alinement with the passages 123, said plungers being located parallel to the longitudinal axis of the head and carrying lugs 131, which are adapted to coact with a cam 132, that is attached to the bridge 129. Upon each plunger is coiled a spring 133. These springs tend to force the plungers into the

passages 123. The cam 132 is disposed in 65 the path of the lugs 131 upon the plungers, whereby, as the head 112 rotates, the plungers are forced against the action of their springs 133 out of the passages 123 before they arrive opposite the passage 111. 70 When a passage 123 arrives at this point, an assembled crown cork will slide into the same and rest upon the platform 124. When then the corresponding lug 131 is disengaged from the cam, the corresponding spring 133 75 forces the plunger against the assembled crown cork, thereby placing the parts under compression and holding them in this condition until the closure makes very nearly a revolution around the shaft 116, when the 80 lug 131 of the plunger again arrives at the cam 132, whereby the plunger 130 is disengaged from the closure, allowing the same to fall, as soon as it drops off the platform 124, into a chute 134, the latter being attached to 85 the arm 125.

While the closures are being carried by the head 112 and held under pressure, their cementing medium is coagulated or set by suitable means. For this purpose a suitable 90 fluid, for instance steam, is admitted into an annular channel 135, that is formed in the annular member 113 in rear of the passages 123. In the channel 135 is provided a radially extending partition 136, the heating fluid being admitted into the channel on one side of said partition, travels around said channel and leaving the same on the other side of the partition. The fluid flows to the channel 135 through a pipe 137, that 95 communicates with a bore 138 in the hub 115, said bore being connected by a pipe 139 with the channel 135 on one side of the partition 136. The other side of the partition is connected by a pipe 140 with a bore 141 100 in the hub 115, said bore communicating with a chamber 142, to which is connected a pipe 143. Stuffing boxes or other suitable means may be provided to prevent a leakage of the fluid in the direction of the longitudinal axis of the shaft 116. The fluid, admitted through the pipe 137 and the passages 105 communicating therewith into the channel 135, flows through the latter and leaves through the pipe 143. The temperature of 110 the fluid is maintained at a point sufficient to coagulate or set the cementing medium within the assembled closures. The coagulation results in a firm union between the parts of the closure.

It is to be observed that upon the machine herein described cementing media can be used which are fed to the caps in their hot state. To the uniting head 112 is led in such cases a cooling fluid.

The transporting means operating mechanism is adapted for use in connection with all assembling machines, where an intermit-

tently moving transporting mechanism is used.

What I claim is:—

1. In a machine for the manufacture of bottle closures of the cap variety, the combination with a rotatable shaft, of a cap transporting mechanism fixedly attached thereto, a reciprocable frame, means mounted upon said frame for depositing a sealing disk into a cap, means for reciprocating said frame, a member oscillatably mounted upon said shaft, a member fixedly attached to said shaft, a connection between said two members for causing the same to move together in one direction, but permitting said shaft to remain stationary upon movement of said oscillatable member in the opposite direction, and coacting means upon said frame and said oscillatable member, whereby intermittent motion is imparted to said transporting mechanism upon reciprocating said frame.
2. In a machine for the manufacture of bottle closures of the cap variety, the combination with a rotatable shaft, of a cap transporting mechanism fixedly attached thereto, a reciprocable frame, means mounted upon said frame for depositing a sealing disk into a cap, means for reciprocating said frame, a member oscillatably mounted upon said shaft, a member fixedly attached to said shaft, a connection between said two members for causing the same to move together in one direction, but permitting said shaft to remain stationary upon movement of said oscillatable member in the opposite direction, coacting means upon said frame and said oscillatable member, whereby intermittent motion is imparted to said transporting mechanism upon reciprocating said frame, means for placing the parts of the closure under compression, and heating means associated with said pressure applying means.
3. In a machine for the manufacture of bottle closures of the cap variety, the combination with a rotatable shaft, of a cap transporting mechanism fixedly attached thereto, a reciprocable frame, means mounted upon said frame for depositing a sealing disk into a cap, means for reciprocating said frame, a flanged member oscillatably mounted upon said shaft, ratchet teeth upon the flange of said oscillatable member, a disk fixedly attached to said shaft, spring pressed pawls upon said disk in engagement with said teeth, and coacting means upon said frame and said flanged member, whereby intermittent motion is imparted to said transporting mechanism upon reciprocating said frame.
4. In a machine for the manufacture of bottle closures of the cap variety, the combination with a rotatable shaft, of a cap transporting mechanism fixedly attached thereto, a reciprocable frame, means mounted upon said frame for depositing a sealing disk into a cap, means for reciprocating said frame, a flanged member oscillatably mounted upon said shaft, ratchet teeth upon the flange of said oscillatable member, a disk fixedly attached to said shaft, spring pressed pawls upon said disk in engagement with said teeth, and coacting means upon said frame and said flanged member, whereby intermittent motion is imparted to said transporting mechanism upon reciprocating said frame.
5. In a machine for the manufacture of bottle closures of the cap variety, the combination with a rotatable shaft, of a cap transporting mechanism fixedly attached thereto, a reciprocable frame, means mounted upon said frame for depositing a sealing disk into a cap, means for reciprocating said frame, a flanged member oscillatably mounted upon said shaft, ratchet teeth upon the flange of said oscillatable member, a disk fixedly attached to said shaft, spring pressed pawls upon said disk in engagement with said teeth, a cam upon said frame, and a lug upon said flanged member, whereby upon reciprocating said frame intermittent motion is imparted to said transporting mechanism.
6. In a machine for the manufacture of bottle closures of the cap variety, the combination with a cap transporting mechanism, of a reciprocable frame, means carried by said frame for charging a cap with a cementing medium, means mounted upon said frame for depositing a sealing disk into the cap on top of the cementing medium, means for reciprocating said frame, means actuated by said frame for imparting an intermittent motion to said transporting mechanism, means for placing the parts of the closure under compression, and heating means for coagulating the cementing medium, the pressure being maintained while said coagulation takes place.
7. In a machine for the manufacture of bottle closures of the cap variety, a rotary head comprising an annular member having radial exterior ribs, a cylindrical member having a curved flange abutting against said ribs and attached to said annular member, whereby a plurality of passages are formed in said head, means for feeding an assembled closure to each of said passages, spring pressed plungers slidably arranged in said cylindrical member in alinement with said passages for applying pressure to the closures in the passages, means for forcing said plungers out of said passages before they arrive opposite to said feeding means, and heating means carried by said head.

8. In a machine for the manufacture of bottle closures of the cap variety, a head rotating around a horizontal axis and comprising a plurality of curved passages, means for feeding an assembled closure to each of said passages, spring pressed plungers slidably arranged in said head in alinement with said passages for applying pressure to the closures in the passages, means for forcing said plungers out of said passages before they arrive opposite to the feeding means, and heating means carried by said head.

9. In a machine for the manufacture of bottle closures of the cap variety, a rotary head comprising an annular member having radial exterior ribs, a cylindrical member having a curved flange abutting against said ribs and attached to said annular member, whereby a plurality of passages are formed in said head, means for feeding an assembled closure to each of said passages, a stationary platform on which the closures rest when arriving in said passages, spring pressed plungers slidably arranged in said cylindrical member in alinement with said passages for applying pressure to the closures in the passages, means for forcing said plungers out of said passages before they arrive opposite to said feeding means, and heating means carried by said head.

10. In a machine for the manufacture of bottle closures of the cap variety, a head rotating around a horizontal axis and comprising a plurality of curved passages, means for feeding an assembled closure to each of said passages, a stationary platform on which the closures rest when arriving in said passages, spring pressed plungers slidably arranged in said head in alinement with said passages for applying pressure to the closures in the passages, means for forcing said plungers out of said passages before they arrive opposite to the feeding means, and heating means carried by said head.

before they arrive opposite to the feeding means, and heating means carried by said head.

11. In a machine for the manufacture of bottle closures of the cap variety, a rotary head comprising an annular member having radial exterior ribs, a cylindrical member having a curved flange abutting against said ribs and attached to said annular member, whereby a plurality of passages are formed in said head, means for feeding an assembled closure to each of said passages, spring pressed plungers slidably arranged in said cylindrical member in alinement with said passages for applying pressure to the closures in the passages, and means for forcing said plungers out of said passages before they arrive opposite to said feeding means, said head being provided with a channel in rear of said passages for the circulation of a fluid medium.

12. In a machine for the manufacture of bottle closures of the cap variety, a head rotating around a horizontal axis and comprising a plurality of curved passages, means for feeding an assembled closure to each of said passages, spring pressed plungers slidably arranged in said head in alinement with said passages for applying pressure to the closures in the passages, and means for forcing said plungers out of said passages before they arrive opposite to the feeding means, said head being provided with a channel in rear of said passages for the circulation of a fluid medium.

Signed at New York, in the county of New York and State of New York, this 8th day of Dec., A. D. 1914.

ALEXANDER BOGDÁNFFY.
